GRINDING DISK

Ingle R. Shue, Beloit, Wis., assignor to Gardner
Machine Company, South Beloit, Ill., a corpo-
ration of Illinois

Application January 7, 1939, Serial No. 249,716

15 Claims. (Cl. 51—209)

The invention relates generally to grinding means and more particularly to a grinding disk adapted to be secured to the face of a supporting wheel and utilizing the face of the disk for grinding purposes.

The general object of the invention is to provide a grinding disk, made either as a unitary structure or comprising a plurality of sections, which is so constructed as to provide a maximum resistance to radial stress.

More specifically, it is an object to provide a grinding disk of unitary or segmental construction adapted to be secured to the face of a supporting wheel, with the grinding disk and supporting wheel so constructed as to provide an interlock resisting radial stress independently of the means for securing the disk and wheel together.

It is also an object to provide a grinding disk of unitary or segmental construction shaped to cooperate with its supporting wheel in such a manner as to resist radial stress and to be secured to said wheel by readily insertable means such as bolts, screws or the like, thus avoiding dependence solely upon such bolts or screws to support the radial stress and permitting use of disks of large diameter rotating at high speeds.

Another object is to provide a grinding disk shaped to provide a maximum resistance, in cooperation with the supporting wheel, to radial stress and providing a maximum depth for the usable portion of the disk.

Other objects and advantages will become apparent from the following description taken in connection with the accompanying drawings, in which—

Figure 1 is a perspective view, partially broken away, of a grinding disk embodying the features of the invention.

Fig. 2 is a fragmentary enlarged sectional view showing the means for securing the disk proper to its supporting wheel.

Fig. 3 is a sectional view similar to Fig. 2 but showing an alternate form of securing means.

Fig. 4 is a perspective view of a segment utilized in making up large disks and constructed similarly to the disks shown in Fig. 1.

Fig. 5 is a perspective view looking upwardly, with parts partially broken away, of a modified form of disk.

Fig. 6 is an enlarged fragmentary sectional view showing the securing means utilized in the disk illustrated in Fig. 5.

Fig. 7 is a view similar to Fig. 6 but showing an alternate form of securing means.

Fig. 8 is a segment utilized in making up large disks and having a construction similar to that shown in Fig. 5.

Fig. 9 is a view similar to Fig. 5 but showing another modified form of construction.

Fig. 10 is an enlarged fragmentary sectional view showing the securing means utilized in the construction illustrated in Fig. 9.

Fig. 11 is a view similar to Fig. 10 showing an alternate form of securing means.

Fig. 12 is a segment utilized in making up large disks and having a construction similar to that shown in Fig. 9.

Fig. 13 is a perspective view showing another modified form of invention in which isolated raised areas are molded as part of the disk.

Fig. 14 is a perspective view illustrating a disk made up of segments such as are shown in Figs. 4, 8 and 12.

20 As mentioned above, the invention herein disclosed relates to grinding wheels utilizing one face for grinding purposes and having its opposite face secured against a supporting wheel, the latter being attached to a drive shaft. The disks herein referred to are such as provide a large facial area across which the work pieces are moved in the grinding operation.

The trend of development in the use of wheels of this character has been towards higher speeds and larger disks. Both of these factors contribute to a necessity for rigidly supporting the disk against radial or centrifugal stress. The trend has also been toward thicker disks so that more wear can be obtained from any given disk before removing it from the machine and replacing it by a new disk. Such increase in thickness necessarily increases weight and consequently results in greater stresses, for which provision must be made.

40 Heretofore disks of this character have been supported against radial stress solely by the means by which the disk proper is secured to its supporting wheel. Usually such means comprises bolts or screws which in the case of high

45 speeds and thick, large diameter disks provide an insufficient factor of safety since the total radial stress exerts a shear on such bolts or screws. Other constructions have been provided to assist in resisting such stress, such constructions utilizing a rim or its equivalent extending from the supporting plate around the periphery of the grinding disk. However, obviously such rims, if they are to extend to sufficient height to be of any great advantage, necessarily limit the depth of the usable portion of the disk.

The embodiments of the invention disclosed herein provide a means for resisting the radial stress independently of the means for securing the disk proper to the supporting wheel. In fact, all radial stress on the bolts or screws may be relieved by the present constructions so that the function of such bolts or screws is merely to clamp the disk proper against the supporting wheel. Moreover, the periphery of the disk is not enclosed so that in the present constructions a maximum usable depth of the disk is attained.

Broadly speaking, the disks disclosed herein attain such result by being so constructed on their rear face and the supporting wheel being so constructed on its front face as to provide an interlock therebetween adequately supporting the wheel against radial stress. Thus while the securing bolts or screws may contribute to such support, the major portion of stress is carried by such interlock. In the case where the disk is made up of a plurality of segments independently secured to the supporting wheel, the advantages of such interlock are greatest. In the case of a complete integral disk the interlock between the grinding disk proper and its supporting wheel resists radial stress which would tend to break the wheel. However, in the case of a disk made up of separate segments, the radial stress upon each segment is not supported by an integral connection with segments having an opposite radial stress. Hence the stress on the screws or bolts, if no interlock were provided, would be excessive, and particularly so because the segmental construction is utilized in the larger size disks. Thus the interlock between the segments and their supporting wheel is particularly advantageous.

From a general aspect, the interlock is provided by providing raised portions on the rear face of the grinding disk, which are adapted to fit into correspondingly shaped depressions in the front face of the supporting wheel, or by the reverse arrangement of providing depressions in the rear face of the grinding disk and correspondingly shaped raised portions on the face of the supporting wheel. Another manner of stating the foregoing is that the grinding disk is provided on its rear face with alternate raised and depressed portions adapted to fit correspondingly shaped raised and depressed portions on the front face of the supporting wheel. Either of these general forms support the disk to resist radial stress, thereby partially or wholly relieving the means by which the disk is secured to the supporting wheel of such stress. Such raised portions are of sufficient area to provide a strength against shear much larger than that of the securing means. Preferably the raised portions may be in the form of one or more annular ribs concentric with the disk, the number of ribs being determined by the size of the disk. Instead of raised portions in the form of annular ribs, such raised portions may be in the form of isolated areas such as round bosses. The ribs of course need not necessarily be annular but may be broadly defined as extending transverse to the radius of the disk thus resisting radial stress.

The ribs or bosses may be molded as part of the abrasive disk, or they may comprise projecting portions of metal rings or parts partially embedded in the disk. In the case of molded raised portions, the part of the securing means which is embedded in the grinding disk may be located in such raised portions. Since such parts limit the depth to which the disk may be used, a greater

usable depth for a given thickness of disk is attained by locating such part of the securing means in the raised portion.

The preferred embodiment of the invention shown in Figs. 1 and 2 comprises a grinding disk, indicated generally at 20, having raised portions on its rear face in the form of one or more annular ribs 21 arranged to fit into annular grooves 22 formed in the front face of the supporting wheel 23. The grinding disk 20 in this instance is shown as comprising a front layer 24 of molded abrasive material constituting the usable portion of the disk, and a rear layer 25 of molded material in which a wire mesh 26 may be inserted for reenforcing the disk. Preferably the mesh is bent out of its plane, as indicated at 27, to follow the contour of the annular ribs 21.

The means for securing the grinding disk to its supporting wheel 23, in this instance, comprises a plurality of nuts 28 adapted to receive screws 29 inserted through the supporting wheel 23 and threaded into the nuts. In the preferred construction the nuts 28 overlie the wire mesh 26, and by locating such nuts in the annular ribs 21, a minimum amount of thickness of the disk is occupied by the nuts and wire mesh so that the usable portion 24 has a maximum depth.

The alternate form of securing means shown in Fig. 3 is utilized in the case where the rear face of the supporting wheel is not readily accessible such for instance as in the case of a vertical spindle grinding machine where the disk rotates within a bowl shaped base. In this instance the securing means comprises washers 30 embedded in the grinding wheel over the inner face of the wire mesh with apertures 31 extending through from the front face of the grinding disk so that a screw 32 may be inserted therein and threaded into the supporting wheel 23.

The securing means may also comprise studs (not shown) having their heads embedded in the disk in a position similar to the nuts 28 or washers 30 and held against turning. The studs project from the rear face of the disk through the supporting wheel to receive nuts at the back of the supporting wheel.

In the case of large disks it is more desirable to provide a disk made up of a plurality of segments such as is shown at 33 in Fig. 4. Each such segment may be constructed in a manner similar to the disk 20, shown in Fig. 1, and be provided with segmental ribs 34 on its rear face which are adapted to fit into annular grooves in the supporting wheel to provide the interlock. Securing means, such as shown in Figs. 2 or 3, may be utilized with such segmental construction.

In the modified form of the invention illustrated in Figs. 5 and 6, one or more annular ribs are formed on the rear face of the grinding disk, indicated at 39, by providing metal rings, indicated generally at 40, partially embedded in the rear portion of the disk. Each such ring preferably comprises a straight sided portion 41 which constitutes the projecting rib adapted to fit in an annular groove 42 in the supporting wheel, and a tapered portion 43 adapted to be embedded in the grinding disk. The embedded portion 43 has its sides tapered toward the straight sided portion 41 so as to firmly hold the disk in place. Each ring 40 may serve as that part of the securing means which is embedded in the grinding disk. For instance, as shown in Fig. 6, the ring 40 is provided with a plurality of threaded apertures 44 to receive screws 45 inserted

through the supporting wheel. In Fig. 7 the ring 40 is shown as provided with countersunk holes to receive screws 46 inserted through the front of the disk and threaded into the supporting wheel. A disk of this construction may be made in the form of a plurality of segments 47 one of which is illustrated in Fig. 8. In the case of such segments, the raised or interlocking rib of the segment is in the form of segmental parts 48 partially embedded in the molded grinding material.

In the form of the invention disclosed in Fig. 9 the disk, indicated at 50, is provided with a plurality of separate partially embedded metal parts 51. Each part 51 has a straight sided portion 52 projecting beyond the plane of the rear face of the grinding disk and into corresponding shaped recesses in the face of the supporting wheel. The portion of each part 51 which is embedded in the grinding disk is preferably tapered to securely hold the disk in place. Such parts 51 are of sufficient dimension to provide adequate strength capable of resisting the tendency to shear produced by the radial stress of the disk. The parts 51 also serve as the embedded portion of the securing means similarly to the rings 41 shown in the previous form. Such parts 51 may be constructed for either of the previously described forms of securing means, as illustrated in Figs. 10 and 11. This form of disk may also be made in segmental construction, as illustrated in Fig. 12. The parts 51 may be arranged in a single row, as shown in Fig. 9, or in a plurality of rows, as illustrated in Fig. 12. The projecting portions of the parts 51 may be round, as indicated at 52 in Fig. 9, or they may be square, as indicated at 53 in Fig. 12.

Fig. 13 shows a construction similar to that shown in Fig. 1 except that the raised portions on the rear face of the grinding disk are isolated and are in the form of bosses 60 instead of the annular ribs 21 of the first form. In this view the disk proper alone is shown. In this case the wire reinforcing mesh, if used, is preferably bent into the bosses 60 and the embedded portions of the securing means are located in the bosses.

Fig. 14 illustrates a complete disk in which the grinding member constitutes a plurality of segments such as are shown in Figs. 4, 8 and 12. Such segments obviously lack the integral connection of the various parts of a unitary grinding disk so that the radial stress on each segment is supported solely by its connection with the supporting wheel. Thus the interlock provided by the present invention is of particular importance in the case of the segmental construction and adequately supports the segments against the radial stress without depending solely upon the securing means for such support.

As a matter of fact, the interlock between the grinding disk and the supporting wheel, in all forms, may be considered as the primary locating means for the disk, and the securing means serves chiefly merely to clamp the disk and wheel together. In practice, there is a small amount of clearance between each bolt and the part through which it passes to facilitate insertion of the bolt after the disk is located by the interlock.

From the foregoing description, it is apparent that I have provided a grinding disk capable of resisting a large radial stress whereby disks of large diameter and thickness may safely be run at high speeds. The interlock provided between

the grinding disk and the supporting wheel, in the various forms shown herein, is capable of supporting such radial stress and relieves the securing means partially or wholly of such stress.

- 5 The raised portions on the rear face of the grinding disk, particularly in the case of constructions utilizing a reinforcing wire mesh, further provide a greater usable depth for disks of predetermined thickness. The greatest advantage occurs in the segmental constructions where the various segments are supported against radial stress solely through their connection with the supporting wheel.
- 10 I claim as my invention:
- 15 1. A grinding wheel comprising, in combination, a supporting member and a grinding member in face to face relation and readily separable from each other, said members being provided with interlocking means to resist radial stress located intermediate the center and periphery of the members, and detachable means extending into the grinding member to secure said members together.
- 20 2. A grinding wheel comprising, in combination, a supporting member and a grinding member in face to face relation, one of said members being provided with areas projecting beyond the plane of the abutting face of the member and the other member being provided with correspondingly shaped depressed areas in its abutting face to provide an interlock therebetween resisting radial stress, and readily detachable means extending into the grinding member to secure said members together.
- 25 3. A grinding wheel comprising, in combination, a supporting member and a grinding member in face to face relation and readily separable from each other, one of said members being provided with one or more annular ribs and the other member with one or more correspondingly shaped annular grooves on their abutting faces, the ribs and grooves interfitting to resist radial stress, and readily detachable means to secure said members together.
- 30 4. A grinding wheel comprising, in combination, a supporting member and a molded grinding member in face to face relation, the grinding member being provided with molded areas projecting beyond the plane of the abutting face thereof, and the supporting member being provided with interfitting depressed areas to provide an interlock resisting relative radial stress, and detachable means for securing said members together having a part embedded in the grinding member and located in said projecting areas whereby a maximum depth for the usable portion of the grinding member is attained.
- 35 5. A grinding wheel comprising, in combination, a supporting member and a grinding member in face to face relation, the grinding member having a reinforcing wire mesh embedded therein adjacent its rear face, said grinding member being provided with areas projecting beyond the plane of the abutting face intermediate the center and periphery with the wire mesh bent to follow the contour of said areas, the supporting member being provided with depressed areas to receive the projecting areas of the grinding member to provide an interlock resisting radial stress, and detachable means for securing said members together, said means having a part embedded in the projecting areas of the grinding member.
- 40 6. A grinding wheel comprising, in combination, a supporting member and a grinding mem-

ber in face to face relation, the grinding member having a plurality of metal parts partially embedded therein and partially projecting beyond the rear face thereof, the supporting member having a plurality of depressed areas in which the projecting portions of said parts fit to resist radial stress, and means extending into the grinding member for securing said parts to the supporting member whereby the grinding member is held in place.

7. A grinding wheel comprising, in combination, a supporting member and a grinding member in face to face relation, the grinding member having one or more rings partially embedded in the rear portion thereof and partially projecting beyond the rear face thereof, the supporting member having one or more grooves in which the projecting portions of said rings fit to resist radial stress, said rings being provided with apertures to receive securing devices extending through the supporting member.

8. A grinding wheel comprising, in combination, a supporting member and a grinding member in face to face relation, the grinding member having a plurality of metal parts each having a portion embedded in the rear part of the grinding member and a portion projecting beyond the rear face thereof, the embedded portion having sides tapered toward the projecting portion to hold the part firmly embedded in the grinding member, the supporting member having a plurality of depressions shaped to receive the projecting portions of said parts, and means for securing said parts to the supporting member to hold the grinding member in place.

9. A grinding wheel comprising, in combination, a supporting wheel and a grinding disk comprising a plurality of segments secured to the face of the supporting wheel and readily separable therefrom, each segment having a plurality of areas projecting beyond the abutting face thereof, the supporting wheel having correspondingly shaped and located depressed areas to receive said projecting areas to provide an interlock resisting radial stress, and detachable means for securing said segments to said supporting wheel at said areas.

10. A grinding wheel comprising, in combination, a supporting wheel and a grinding disk comprising a plurality of segments secured to the supporting wheel in face to face relation, each segment having one or more segmental ribs on its abutting face, the supporting wheel having one or more annular grooves shaped to receive

said ribs to resist radial stress, and detachable means located at said ribs for securing said segments to the supporting wheel.

11. A grinding disk having one or more raised areas projecting beyond the plane of the rear face of the disk and located intermediate the center and periphery of the disk, the raised areas being provided with means extending into the disk by which the disk may be detachably secured to the face of a supporting wheel, the raised areas being adapted to interfit with depressions in the face of the supporting wheel.

12. A grinding disk made of molded abrasive material and having one or more raised portions molded on its rear face intermediate the center and periphery of the disk, and means by which the disk may be secured to the face of a supporting wheel embedded in said molded raised portions, said portions being adapted to fit into depressions in the face of the supporting wheel to provide an interlock resisting radial stress.

13. A grinding disk comprising a plurality of segments, each segment having a plurality of segmental ribs concentrically arranged projecting beyond the rear face of the segment in spaced relation to each other and to the center and peripheral edge of the segment, and detachable means located in said ribs for securing the segment to a supporting wheel.

14. A grinding disk adapted to be removably secured to the face of a supporting wheel and having one or more portions on its rear face offset from the plane thereof and spaced from the center and periphery of the disk for interlocking engagement with complementarily shaped areas on the front face of the supporting wheel, and means embedded in said disk for detachable engagement by securing means for holding the disk in face to face engagement with the supporting wheel.

15. A grinding wheel comprising, in combination, a supporting member and a grinding member in face to face relation, and detachable means to secure said members together whereby said member may be readily separated from each other, one of said members being provided with one or more ribs extending generally transverse to the radius of the member and the other member with one or more correspondingly shaped and correspondingly located grooves on their abutting faces, the ribs and grooves interfitting to resist radial stress.

INGLE R. SHUE.
